UNITED STATES PATENT OFFICE.

ALFRED A. SPADONE, OF NEW YORK, N. Y.

DESIGN FOR A COMBINED WRENCH AND SPANNER.

SPECIFICATION forming part of Design No. 24,773, dated October 22, 1895.

Application filed August 23, 1895. Serial No. 560,289. Term of patent 7 years.

To all whom it may concern:

Be it known that, I ALFRED A. SPADONE, a citizen of the United States, residing at New York, in the county of New York and State of New York, have invented a certain new and original Design for a Combined Wrench and Spanner; and I do hereby declare the following to be a full, clear, and exact description of the design, such as will enable others skilled in the art to which it appertains to make and use the same, reference being had to the accompanying drawings, and to letters of reference marked thereon, which form a part of this specification.

Figure 1 is a plan elevation of a combined wrench and spanner, showing my design. Fig. 2 is an end elevation of the same; and Fig. 3 is a sectional view on the line $x-x$ of Fig. 1, these views being deemed necessary to fully illustrate my design.

e represents the handle, through which is made the opening a . That portion f of the handle which is grasped by the hand has the outline shown and in cross-section is approximately diamond-shaped, as represented in Fig. 3. The front end b of the wrench is curved, as shown, forming a segment of a circle, and through the two projecting portions c are formed the circular openings d .

Having thus described my invention, I claim—

The design for a combined wrench and spanner, substantially as shown and described.

In testimony that I claim the invention set forth above I have hereunto set my hand this 9th day of May, 1895.

ALFRED A. SPADONE.
